Ruth S. M. Schroeder,
INVENTOR

By

Warren R. Dahlstrom
Attorney

UNITED STATES PATENT OFFICE.

RUTH S. M. SCHROEDER, OF CHICAGO, ILLINOIS.

TOILET ARTICLE.

Application filed June 5, 1922. Serial No. 566,061.

To all whom it may concern:

Be it known that I, RUTH S. M. SCHROEDER, a citizen of Sweden, with a pending application for U. S. citizenship, and residing at Chicago, in the county of Cook and State of Illinois, have invented a certain new and useful Improvement in Toilet Articles, of which the following is a specification.

My invention relates to toilet accessories and has particular reference to devices for curling, marcelling or waving the hair, and its objects are to provide a device that is light, easily applied and removed, and which will produce a more permanent waving or curling of the hair than is accomplished by the devices heretofore provided. A further object is to make my device of a form and construction which adapts it to be worn as a hair ornament while acting as a curling device.

And with the above named general objects in view my invention consists in the novel construction, combination and arrangement of parts hereinafter described in detail, illustrated in the accompanying drawing, and more particularly pointed out in the appended claims.

In the drawing—

Figure 1 is the outline of the upper portion of a woman's figure showing the application of my invention.

Figure 2 is a view of the device in the position in which it is held in Figure 1.

Figure 3 is a view of Figure 2 in a vertical plane at right angles to the plane of Figure 2.

Figure 4 is a view of the device in its operative or closed position taken in the plane of Figure 2.

Figure 5 is similar to Figure 4, but in a plane at right angles thereto.

In the several views 2 and 3 are preferably arms or branches in the form of elongated wire loops which form a clasp between the members of which is clamped the coil or winding of hair —5— on an intermediate arm, branch or pin 4. The members 2, 3 and 4 may be made in any suitable manner and of various configurations, but by making the loops or arms out of wire makes the structure lighter than if made of plate metal. In Figure 1 the device, or curler, is shown as held by the left hand while the right hand is winding a lock, or strands, of hair on the intermediate member 4. The latter is preferably wider, as shown, at its outer or free

end so as to wedge the hair wound upon it tightly inwardly or toward the juncture of the three arms 2, 3 and 4, or to guard against any tendency of the coil to slide off the member 4. But its outlines may be varied in numerous ways.

The arm 2 is perhaps most conveniently placed innermost, or against the head of the user, in which event the arm 3 will be the outer or exposed arm and the only part that is exposed to view, and while this outermost arm is shown as of plain wire loop design it is obvious that it may take any of the well known, or other, ornamental hair pin or hair ornament designs. My improvement may therefore be worn throughout the day as well as during the usual resting periods. As suggested in Figure 1 a plurality of these hair curlers may be arranged to serve, when designed for that purpose, as hair ornaments as well as curlers.

The present improvement is designed both to facilitate the usually inconvenient process of hair curling and to give greater permanency to the curls when formed by placing the curl 5 under pressure between the arms 2 and 3 while it is becoming "set," as illustrated in Figures 4 and 5. The full lines of Figure 2 show substantially the relative positions of the arms while the winding is done on the arm 4. When the winding is completed the arm 3 is folded on or over the arms 2 and 4, the arms moving together on their pivot portions at 10 on a band or pivot member 11 to which the arm 4 is preferably secured at its ends—12 and 13. When folded the arms 2 and 3 are held clasped upon the coil 5 by a catch 7 pivoted at 6 and having a concave or hook portion 8 which is engaged with the free end of the arm 3. The catch 7 has a finger grip portion, or outstanding lug or lip 9 which, when in operative position projects slightly beyond the arm 3 as shown in Figure 4, whereby it is made conveniently accessible to hook or unhook the clamp of the curler. The greater the tension upon the member 7 the more securely will it hold the parts together. At the same time it is instantaneously releasable by a slight outward pull on the lip or lug 9.

I claim as my invention—

1. A hair curler consisting of three loops of wire forming arms, said arms being pivoted together at their ends for free angular movement relative to each other, one

of said arms adapted to serve as a winding member or core upon which a lock of hair may be wound as a coil, and means for sustaining pressure by the other arms upon

5 said coil to increase its permanency.

2. A hair curler consisting of a bar or arm upon which a coil of hair may be wound, pivotally movable loop-shaped arms, the opposite side of each loop to be pressed into

10 and form depressions in said coil and means for clamping same against said coil.

3. The combination with a winding member adapted to serve as a winding core supporting a coil of hair, of auxiliary loop members pivoted to be moved against opposite sides of said coil and a clasp pivoted to one of said members to engage the other member and press the sides of said loop into said coil.

In testimony whereof I have hereunto

signed my name.

RUTH S. M. SCHROEDER.
